UNITED STATES PATENT OFFICE.

ALFRED BIRNIE, OF SPRINGFIELD, AND CHAUNCEY W. GAY, OF WEST SPRINGFIELD, MASSACHUSETTS.

APPARATUS FOR CARBONATING AND DELIVERING LIQUIDS.

SPECIFICATION forming part of Letters Patent No. 674,492, dated May 21, 1901.

Application filed May 14, 1900. Serial No. 16,581. (No model.)

To all whom it may concern:

Be it known that we, ALFRED BIRNIE, a resident of Springfield, and CHAUNCEY W. GAY, a resident of West Springfield, in the county of Hampden and State of Massachusetts, citizens of the United States of America, have invented certain new and useful Improvements in Apparatus for Carbonating Liquids and Delivering Same, of which the following is a full, clear, and exact description.

The object of this invention is to provide a bottle or like receptacle for water or other liquids to be carbonated and appliances for use in conjunction therewith, so that as desired the water may be impregnated with the carbonic-acid gas and so that at any time desired any portion of the carbonated water or other liquid may be withdrawn without liberating the gas from the bottle which remains therein impregnated in the portion of the contents of the bottle which may not have been withdrawn. In other words, the object is to insure that however little of the liquid may remain in the bottle after some thereof has been withdrawn such remaining portion of the liquid will be of the same effervescent quality as that first withdrawn.

To these ends the invention consists in the combinations of parts and appliances, all substantially as hereinafter fully described, and set forth in the claims.

The improved carbonating apparatus is illustrated in the accompanying drawing, in which the figure is a central vertical sectional view of the same.

In the drawing, A represents a bottle for water or other liquid desired to be carbonated, the same having applied at the mouth end *a* thereof the metallic chambered part B, having a screw-thread engagement, as seen at *b*, with the mouth portion of the bottle proper, having the intermediate enlargement or hollow bulb-like portion *d*, terminating at the ends opposite that screw engaging with the bottle-neck in the externally-screw-threaded axial hub-like part *f*. This part *f* has an entrance-opening, fitted in which is a plug or stopper *g*, provided with an outwardly-extending spur *h* and one or more minute passages *i*, leading from the outer end of the plug *g* to communicate with the

tube *j*, which is screw-engaged with the inner end portion of the plug and extends centrally and axially through the enlargement *d* and well into the interior of the bottle 55 proper, A.

k represents a packing of annular form fitted in the opening or passage through the portion *f* of the metallic appliance B, which is provided as an extension of and may be understood as a portion of the bottle, although for purposes of practicability this portion B is made separately and preferably of metal and screw-connected with the bottle, which will be usually of glass.

D represents a suitably massive and substantial or stable base, having therein the upwardly-opening socket *E*, of considerable depth, as shown, and having in the orifice of said socket the internal screw-threads *m*, 70 screw-engaging with which are the external screw-threads of the aforesaid hub-like portion *f* of the metallic appliance provided as an extension of the neck of the bottle. The said socket *E* is shaped and adapted for the 75 reception therein of a capsule *x*, containing carbonic-acid gas under suitable compression. The capsule is of bulb or pear form, with its end which is to be pierced for the liberation of the gas uppermost. The appliance B is provided with a cock *n*, closing the passage *o*, which when the valve *t* is forced open is opened for the passage of the liquid from the bottle through the downwardly-directed nozzle *u*.

The operation of the improved appliances will be now explained. The bottle having been filled with pure water or other liquid which it is desired shall be carbonated, which filling is performed by the removal of the appliance B from the neck of the bottle, said appliance being thereafter replaced, the capsule *x* is dropped and sunk into the socket *E* therefor in the base-support *D*. The bottle having as a part thereof the said enlargement 90 B, provided with the equipments before referred to, is by the threaded portion *f* screwed down into the orifice of the socket in the base, forcibly carrying the spur to pierce the upper end of the capsule, whereby the gas therein 95 contained under comparatively great pressure is liberated and passes through the nee-

ble-ducts *i* into the extension-tube *J* and issues from the upper end thereof and thoroughly commingles with and impregnates the liquid with which the bottle is quite or 5 partially filled, as the case may be.

It will be apparent that the base *D* constitutes a sufficiently stable support for the inverted bottle and that the downwardly-directed nozzle *u* has its position at such a 10 height above the bottom of the base that a glass resting on the same table or support with the base, suitably adjacent the latter, may receive therein the carbonated liquid by inwardly pressing the knob-like end of the 15 stem of the valve *t*.

It will be manifest from the construction and arrangement of the parts and the capabilities thereof for utilization that the portion of the liquid withdrawn from the bottle 20 is carbonated in the same degree as the portion remaining in the bottle and that the remaining portion remains carbonated and is without deterioration in respect of its effervescence until withdrawn, whether the withdrawal be soon or delayed for a comparatively long time.

We are aware that appliances and receptacles for carbonating liquids have been employed wherein the gas introduced from the 25 capsule for the impregnation of the liquid has been performed by the piercing of the capsule and permitting the gas to reach the interior of the bottle and its contents through a tube; but in such an apparatus it has been necessary when desired to use the contents to first secure the exhaustion of the greater 30 part of the gas from the bottle without the withdrawal of the liquid and then to pour the liquid, remaining partially carbonated, out 35 through the mouth proper of the bottle. This has necessitated for fairly satisfactory results the utilization of all of the contents of the bottle at one pouring; but as dependent upon the new arrangements and combinations 40 of parts and appliances making up this invention as much or as little of the liquid may be withdrawn at any time or times as 45 may be desired, and such liquid so withdrawn is charged with the gas to the maximum degree.

While we regard the enlarged or bulb-like formation of the appliance *B* a preferable one, as it provides ample space for occupancy of a portion of the liquid of the bottle when the 50 latter is inverted, leaving a relief or vacant space within the liquid-containing receptacle, as a whole we do not limit ourselves

strictly thereto, nor necessarily to separable formations of parts of the bottle proper, *A*, and the portion or extension thereof equipped 60 with the part which screw-engages into the orifice of the socket in the base and with the downwardly-directed valve-nozzle.

Having thus described our invention, what we claim, and desire to secure by Letters Patent, is—

1. In an apparatus of the character described, the combination with the base *D* having the upwardly-opening socket *E* for the reception therein of a gas-containing capsule, 70 and having its orifice internally screw-threaded, of the bottle having a substantially closed hollow neck extension the extremity of which is externally screw-threaded to screw-engage in the orifice of said socket and having a minute gas duct or ducts leading into the interior of the bottle, provided with the downwardly-extending spur *h* and said neck extension being provided with the laterally-located downwardly-turned, passaged nozzle *u* 80 the lower end of which is suitably above the bottom of the base, and a valve for normally closing the passage through said nozzle, substantially as described.

2. In an apparatus of the character described, in combination, the bottle proper *A* having the appliance *B* constituting a neck extension of the bottle, one end of which screw-engages the bottle, and the other end portion *f* of which is formed hub-like and externally screw-threaded, and provided with the plug or stopper section *g* constructed with the downwardly-extending spur *h* and with the upwardly-leading gas duct or ducts *i*, *i*, the tube *j* provided to the part *g*, and rising therefrom into the inverted bottle, with which said ducts communicate, said neck extension moreover being provided with the laterally-located, downwardly-turned nozzle *u* having the valved passage *o* therethrough, and the base *D* having the deep capsule-receiving socket *E*, within the orifice of which are the screw-threads for the engagement therewith of the said hub-like portion *f* of the bottle-neck extension, all substantially as and for 105 the purposes set forth.

Signed by us at Springfield, Massachusetts, this 26th day of March, 1900.

ALFRED BIRNIE.
CHAUNCEY W. GAY.
